United States Patent Office

Des. 176,312
Patented Dec. 13, 1955

176,312

REAR VIEW MIRROR

Rene Daon, Norwalk, Conn., assignor to Supersite Corporation, New York, N. Y., a corporation of New York

Application February 23, 1954, Serial No. 29,161

Term of patent 14 years

(Cl. D14—6)

FIG. 1

FIG. 2

FIG. 3

Figure 1 is a top plan view of a rear view mirror embodying my new design;

Figure 2 is a side elevational view thereof; and

Figure 3 is a rear view.

The face of the mirror is plain and conventional.

I claim:

The ornamental design for a rear view mirror, as shown and described.
